United States Patent Office.

HENRY M. WOODFORD, OF KENSINGTON, CONNECTICUT.

Letters Patent No. 79,426, dated June 30, 1868.

IMPROVED MATCH-SAFE.

The Schedule referred to in these Letters Patent and making part of the same.

TO ALL WHOM IT MAY CONCERN:

Be it known that I, HENRY M. WOODFORD, of Kensington, county of Hartford, and State of Connecticut, have invented certain new and useful Improvements in the Manufacture of Match-Safes; and to enable others skilled in the art to make and use the same, I will proceed to describe, by referring to the drawings, in which the same letters indicate like parts in each of the figures.

The nature of this invention consists in producing the whole device or safe complete in three pieces of metal, and, further, in securing the whole together by simply heading the rivets.

In the accompanying drawings—

Figure 1 is a face view of the box, as in a finished state.

Figure 2 is an edge view or a section view, showing its construction.

a is the bracket or plate, to which the boxes and lid are secured, which are made of any desirable figure or pattern to suit the taste.

c are screw-holes, for securing the device on the wall or in place for use.

d is a rough friction-surface, for igniting the match.

e is a match-receptacle.

e' is a lid to said receptacle.

f is a waste-box.

g is a bracket, cast or produced in one and the same piece of metal with the boxes *e f*.

h are bearing-depressions, formed on the back, side, and near the upper edge of the lid *e'*.

k are depressions or openings, formed in the bracket *a*, to allow free action of the lid-hinge pins *i* formed on the lid *e'*.

Now, it will be seen that, when the parts are all cast in readiness for being put together, it is only necessary to arrange the parts as shown, (in fig. 1,) then heading down the fastening-rivet *n*, when the article will be in readiness for use.

I believe I have thus shown the nature, construction, and operation of this improvement, so as to enable others skilled in the art to make and use the same therefrom.

What I claim, therefore, and desire to secure by Letters Patent, is—

A match-safe, constructed substantially as shown and described, as an article of manufacture.

HENRY M. WOODFORD. [L. s.]
